US00D934869S

(12) **United States Design Patent** (10) Patent No.: **US D934,869 S**
(45) Date of Patent: ** Nov. 2, 2021

(54) **SLEEVE FOR ELECTRONIC DEVICE**

(71) Applicant: **Catalyst Lifestyle Limited**, North Point (HK)

(72) Inventors: **Joshua Wright**, Hong Kong (CN); **June Lai**, Hong Kong (CN)

(73) Assignee: **CATALYST LIFESTYLE LIMITED**, Hong Kong (CN)

(**) Term: **15 Years**

(21) Appl. No.: **29/724,348**

(22) Filed: **Feb. 14, 2020**

(30) **Foreign Application Priority Data**

Oct. 31, 2019 (CN) 201930596466.6

(51) LOC (13) Cl. **14-02**

(52) U.S. Cl.

USPC **D14/440**; D3/218

(58) **Field of Classification Search**

USPC D14/440, 447, 250; 206/45.23, 320, 206/45.2; 361/679.55; 294/25; 224/218; D3/294, 218; D9/420

CPC ... G06F 1/1628; G06F 1/1626; A47B 23/044; A45C 11/00; H04B 1/3888
